UNITED STATES PATENT OFFICE.

ERNEST G. DANIELSON, OF SAN FRANCISCO, CALIFORNIA, ASSIGNOR TO GRAY & DANIELSON MFG. CO., OF SAN FRANCISCO, CALIFORNIA, A COPARTNERSHIP.

ROTARY SPARK-GAP APPARATUS.

Application filed October 30, 1919. Serial No. 334,604.

To all whom it may concern:

Be it known that I, ERNEST G. DANIELSON, a citizen of the United States, and a resident of the city and county of San Francisco, State of California, have invented a certain new and useful Rotary Spark-Gap Apparatus, of which the following is a specification.

The invention relates to rotary spark gap devices for use in radio signaling systems.

An object of the invention is to provide a rotary spark gap apparatus in which the phase relation of the radio frequency current may be varied without disturbing the concentricity of the rotor and stationary electrode holder.

Another object of the invention is to provide a rotary spark gap apparatus which may be readily adjusted to compensate for wear or other purposes.

A further object of the invention is to provide a reliable and efficient fool-proof device.

The invention possesses other advantageous features, some of which, with the foregoing, will be set forth at length in the following description, where I shall outline in full, that form of the invention which I have selected for illustration in the drawings accompanying and forming part of the present specification. In said drawings, I have shown one embodiment of my invention, but it is to be understood that I do not limit myself to such form, since the invention, as set forth in the claims, may be embodied in a plurality of forms.

Referring to said drawings:

Figure 1 is a front elevation of the apparatus of my invention.

Figure 2 is a vertical longitudinal section through the apparatus taken on the line 2-2, Figure 1.

Figure 3 is a front elevation on a larger scale of the stationary electrode holder.

Figure 4 is a side elevation of the stationary electrode holder.

Figure 5 is a section through the stationary electrode holder taken on the line 5-5, Figure 4.

The apparatus comprises a rotor having electrodes fixed thereon, and a stationary electrode supporting member upon which are arranged movable stationary electrode holders. The stationary electrodes are adjustable radially in the holders so that they

may be readily moved to produce the required spark gap and the holders are pivotally mounted on their supporting member so that, in the event of accident, improper adjustment or accumulation on the ends of the electrodes, the stationary electrodes may be swung or pushed from the path of the moving electrodes without injury thereto. The stationary electrode supporting member is movable circumferentially to vary the phase relation of the current and in order to insure concentricity of this member with the rotor at all times, the rotor is journaled in the member.

The apparatus comprises a stationary electrode supporting member comprising a disc 2 which is suitably mounted in a housing 3, so that it may be moved circumferentially, a handle 4 being usually provided for that purpose. Mounted on the disc 2, and insulated therefrom by the insulators 5, which extend through the disc, is a plurality of conducting posts 6, in the present instance there being four posts 6. Secured to the ends of the posts 6 are two arc-shaped conducting bars 7, each bar being connected to two adjacent posts and the two bars being separated from each other, at the ends of the arcs. A conductor is connected to either of the posts of a bar 7.

Mounted on the bars 7, and equidistantly spaced circumferentially, are four stationary electrode holders 8, each holder being pivoted to the bar 7 to one side of the radius through the stationary electrode. For this purpose each holder is provided with an ear 9, through which passes a screw 12, which engages in the adjacent conducting post 6. The screw is provided with a smooth shank at that part which lies within the ear, and a spring washer 13 is interposed between the ear and the bar. The screw is sufficiently tight, so that normally the holder remains stationary, and is so held that a shock or blow on the stationary electrode will cause the holder to swing on its pivot, or screw 12.

Disposed in the holder 8 is the angular shank 14 of the stationary electrode 15, which is of considerable length and which presents a large sparking surface 16. This sparking surface is preferably parallel to the axis of rotation of the rotor. The shank 14 is provided with a recess 17, and terminating at the bottom is a threaded hole, in

which the adjusting screw 18 engages. The holder is closed at the top by a plate 19, having an aperture through which the screw 18 passes freely, and against the upper surface of which, the shoulder 21 of the screw rests. A spring 22 is disposed in the recess 17 in the shank to hold the electrode pressed outward from the holder. The electrode may be readily removed for purposes of repair or renewal, by rotating the head 23 of the screw. The holder is closed at the front by a plate 24, and secured by the screws 25, which hold the plate 24 in place, is a flat spring 26 having a tooth or projection 27 at its upper end, which engages in regularly spaced depressions 28 on the head of the screw. The angular distance between the depressions is preferably so related to the pitch of the screw thread, that a movement 20 of the head through such angular distance moves the electrode .005 inches, the desired spark gap. The holder is prevented from moving inwardly, and is positioned in proper adjustment on the bar, by a set screw 31, 25 passing radially through a bracket 32 on the holder and contacting with the peripheral surface of the bar. This insures the proper operative position of the holder and the electrodes.

30 The disc or plate 2 is provided with tubular extensions 33 on opposite sides thereof, in which are arranged bearings in which the shaft 34 of the rotor is journaled. The shaft is, therefore, journaled in the stationary electrode supporting member and, being concentric therewith, adjustment of the disc does not destroy the concentricity. The rotor comprises a metallic carrier or drum 35 secured to the shaft and provided with regularly spaced projections or teeth 36 which constitute the rotary electrodes. These electrodes are preferably of the same length as the stationary electrodes and present the same large, uniform sparking surface. The 45 uniform sparking surfaces produce a uniform note when the apparatus is in operation. The shaft 34 is usually rotated by an electric motor at the desired speed, and an insulating coupling is arranged in the shaft 50 between the device and the motor.

By virtue of this construction, the stationary electrodes may be readily and easily adjusted to compensate for wear and may be quickly replaced when required. An improper adjustment of the stationary electrode or an accumulation on the sparking surfaces of one or more electrodes will not result in the destruction of the apparatus when in operation, but will merely cause 55 one or more of the stationary electrodes to be thrown outward.

I claim:

1. A rotary spark gap apparatus, comprising a stationary support, a stationary-electrode supporting member rotatably mounted at its outer portion in said support and a rotary electrode carrier having its journal in said member so that its journal rotates therewith.

2. A rotary spark gap apparatus, comprising a stationary support, a circular stationary-electrode supporting member rotatably mounted at its periphery in said support, a shaft having its journal in said member and a rotary electrode drum secured to said shaft.

3. A rotary spark gap apparatus, comprising a stationary-electrode supporting member, electrode holders pivotally mounted in a circle on said member, electrodes carried by said holders, and a rotary electrode carrier journaled in said member.

4. In a rotary spark gap apparatus, an electrode supporting member, an electrode holder pivotally attached to said member, an electrode in said holder, and a screw carried by the holder and adapted to engage the periphery of the member to position the holder with respect to the member.

5. In a rotary spark gap apparatus, a circular, stationary-electrode supporting member, a rotary electrode member arranged concentrically within said first mentioned member, stationary electrodes, and means for supporting said stationary electrodes on said first supporting member whereby said stationary electrodes may be freely moved outwardly as to said member.

6. In a rotary spark gap apparatus, an electrode holder, a circular holder supporting member, means for movably securing said holder to said member, whereby said holder may swing outwardly radially as to the supporting member, and an electrode in said holder.

7. In a rotary spark gap apparatus, an electrode holder, comprising a body portion having a seat therein, an electrode disposed in said seat, a screw extending into said body and said electrode for varying the position of the electrode with respect to the body, a head on said screw having depressions therein, and a spring secured to said body and bearing against said head.

In testimony whereof, I have hereunto set my hand at San Francisco, California, this 21st day of October, 1919.

ERNEST G. DANIELSON.
